[57] CLAIM

The ornamental design for a plumbing enclosure, as shown and described.

DESCRIPTION

FIG. 1 is a perspective view taken from the top, front and left side of an enclosure for bathing showing our new design;

FIG. 2 is a front elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a rear elevational view thereof;

FIG. 8 is a top plan view of a second embodiment thereof, which is a mirror image of the first; and,

FIG. 9 is a sectional view taken on line 9—9 of FIG. 3. The fragmentary broken line representations of a hole in FIGS. 1, 6, and 9 are for the purpose of illustration only and form no part of the claimed design.

The characteristic feature of our design resides in a horizontal band along the rear of the enclosure, the band having a series of diamond-shaped elements.
